UNITED STATES PATENT OFFICE.

PHILIBERT BONVILLAIN, OF PARIS, FRANCE.

OIL OR OTHER FILTER PRESS.

SPECIFICATION forming part of Letters Patent No. 678,858, dated July 23, 1901.

Application filed August 11, 1900. Serial No. 26,546. (No model.)

To all whom it may concern:

Be it known that I, PHILIBERT BONVILLAIN, consulting engineer, a citizen of the Republic of France, residing at Paris, 6 Rue Blanche, 5 in France, have invented certain new and useful Improvements in or Relating to Oil and other Filter Presses, of which the following is a specification.

The present invention has for its object a 10 box made up of metallic rings, which are placed one upon the other and having interposed circular wicks or filtering means, with or without metallic cores, which offer a large filtering-surface. More particularly this box 15 is applicable for oil-presses, but it can of course be employed for any kind of filter-presses desired.

Generally ordinary boxes made with vertical bars have in practical use the inconvenience that they only offer a very weak filtering-surface to the oil, which thereby meets a too great resistance to escape freely from the box. If in order to overcome this difficulty the space between the bars forming the box 25 is increased, even slightly, a great quantity of meal escapes with the oil, which spoils it. Moreover, the meal thus carried away constitutes a loss, since it cannot be utilized except for mixing with material for the second 30 pressing.

In order to obtain with filtering cages and rings the same filtering-surface as with bags and the like, a very simple form of construction according to the present invention will 35 be described with reference to the accompanying drawings, in which—

Figure 1 is a vertical section through the box, taken on the line 5 5 of Fig. 2. Fig. 2 is a horizontal section on the line 6 6 of Fig. 1. 40 Fig. 3 is a section, on an enlarged scale, of a ring; Fig. 4, a modified shape of a ring shown in section, on a reduced scale.

The box into which the meal to be pressed is introduced consists of a series of circular 45 rings *a a*, arranged one above the other, perfectly concentric, and fitted by means of a circular flange *b* on the upper face of one ring fitting in a corresponding recess *c* on the under side on the ring above. Each ring *a* is 50 provided with a worked flat part *d* upon its under side and a similar surface on its upper side, so that when superposed the rings

fit closely at *d* and *e* in a perfect manner above each other. This arrangement has the advantage that the rings need only be 55 worked on their fitting faces. Each ring is provided on its upper side with a circular groove *f* and with radial cuts or slots *g g* at equal distances apart. The groove *f*, preferably of rectangular shape, Figs. 1 and 3, or 60 of any other shape in cross-section, is provided to receive a filtering wick or packing *h*, which is fitted internally with a metallic wire *i* of suitable shape, preferably flat or circular, as shown in the drawings. These 65 wicks are slightly compressed by the rings when in place. Each set of rings forming a box are arranged between two much thicker circular rings *k l*, with projections to receive clamping-bolts *m m*. The radial cuts *g g* 70 serve for the escape of the oil to the filtering-wicks *h h*, a large filtering-surface being thus obtained, which facilitates considerably the passage of the extracted liquid. Moreover, the wicks retain the meal, which cannot escape with the liquid. Moreover, the metallic core *i* in the interior of the wicks serves to 75 prevent these wicks from becoming too hard and too thick under the internal pressure and maintain their filtering qualities. The 80 wicks *h h* can be made of hairs, malfil, felt, or any other convenient material, according to the nature of the meal to be pressed.

Having now particularly described and ascertained the nature of this invention and in 85 what manner the same is to be performed, I declare that what I claim is—

1. A filter-press comprising a series of rings and means for securing the same together, each ring being provided with a longitudinal 90 groove and a filtering-wick in said groove, and also being provided with radial grooves adapted to permit the escape of the liquid to be filtered, substantially as herein set forth.

2. A filter-press comprising a series of rings 95 and means for securing the same together, each ring being provided with a longitudinal groove and a filtering-wick provided with a metallic core in said groove, and also being provided with radial grooves adapted to permit the escape of the liquid to be filtered, substantially as herein set forth.

3. In a filter-press, a ring provided with means for fitting and securing the same to

other rings in a series, and provided with a longitudinal groove, a filtering-wick in said groove, and a series of radial grooves adapted to permit the escape of the liquid to be filtered, substantially as herein set forth.

4. In a filter-press, a ring provided with means for fitting and securing the same to other rings in a series, and provided with a longitudinal groove, a filtering-wick provided with a metallic core, in said groove, and a series of radial grooves adapted to permit the escape of the liquid to be filtered, substantially as herein set forth.

5. In a filter-press, the combination with filtering-wicks provided with metallic cores, 15 of frames or holders therefor provided with means for slightly compressing the wicks, and with means for permitting the passage of the liquid to be filtered to, through, and from the said wicks, substantially as herein set forth. 20

Signed at Paris, France, this 30th day of July, 1900.

PHILIBERT BONVILLAIN.
